BEER DISPENSING SYSTEM

Abraham Cohen, Brooklyn, N. Y., assignor, by
mesne assignments, to Beer Control Systems,
Incorporated, a corporation of New York

Application October 6, 1934, Serial No. 747,185

16 Claims. (Cl. 225—12)

This invention relates to beer dispensing systems.

An object of this invention is to provide a system of the character described, provided with highly improved means for returning the beer within the beer coils to the barrels and for flushing the coils with water and draining the water from the coils.

A further object of this invention is to generally improve the beer dispensing system disclosed in my co-pending application Serial No. 689,831, filed on the 18th day of September, 1933.

Still another object of this invention is to provide a durable beer dispensing system of the character described, which will comprise comparatively few and simple parts, be relatively inexpensive to manufacture, smooth and positive in operation, simple to manipulate and withal practical and efficient to a high degree in use.

Other objects of this invention will in part be obvious and in part hereinafter pointed out.

The invention accordingly consists in the features of construction, combinations of elements and arrangement of parts which will be exemplified in the construction hereinafter described, and of which the scope of application will be indicated in the following claims.

In the accompanying drawings, in which is shown one of the various possible embodiments of this invention,

Fig. 1 is a front elevational view of a beer dispensing system embodying the invention,

Fig. 2 is a side elevational view of a part of the structure shown in Fig. 1,

Fig. 3 is a top plan view of a valve head forming part of the invention,

Fig. 4 is a cross-sectional view taken on line 4—4 of Fig. 3,

Fig. 5 is a cross-sectional view taken on line 5—5 of Fig. 3,

Fig. 6 is a cross-sectional view taken on line 6—6 of Fig. 3,

Fig. 7 is a cross-sectional view taken on line 7—7 of Fig. 3,

Fig. 8 is a cross-sectional view taken on line 8—8 of Fig. 6,

Fig. 9 is a partial cross-sectional view of a portion of the valve shown in Fig. 5 disclosing the same in another position,

Fig. 10 is a view similar to Fig. 9, but disclosing still another position of the valve,

Fig. 11 is an enlarged cross-sectional view of the valve control forming part of my invention; and

Fig. 12 is an enlarged cross-sectional view of

the handle forming part of the valve control shown in Fig. 11.

Referring now in detail to the drawings, 10 designates a beer dispensing system embodying the invention, wherein the beer barrels 11 are located in the cellar on the cellar floor 12, and the bar counter 13 is located on the floor above, being mounted on the floor 14. The system may be controlled by a control mechanism 16 fixed to the bar counter 13. In the drawings there is illustrated a system for dispensing beer from two barrels 11, although the same principle may be applied for dispensing beer from and controlling any suitable number of barrels.

The counter 13 may be of any suitable usual construction and is provided with a pair of beer faucets 17 interconnected by pipe 18. Mounted within the counter are a pair of cooling or beer coils 19, each interconnected through pipe 20 to the pipe 18. Located on the cellar floor 12 is an air or carbon dioxide pump 22 having a pressure tank 22a for supplying pressure to the barrels, as explained hereinafter.

Fixed to a support 23 within the cellar is a valve head 25. Said valve head 25 comprises a casting 26 fixed as by bolts 27 to the wall 23. As will appear hereinafter, the valve head 25 is symmetrical with respect to the mid-section thereof, one side being connected to one of the beer barrels and one of the coils 19, and the other side being connected to the other beer barrel and the other coil.

The casting 26 is formed with a pair of central valve chambers 28, a second pair of valve chambers 29 disposed on opposite sides of the chambers 28, and an outer pair of chambers 30. The chambers 28 are formed with screw threaded openings 28a in the bottom walls thereof, the chambers 29 with screw threaded openings 29a at the bottom thereof, and the chambers 30 with screw threaded openings 30a at the bottom walls thereof.

Screwed within the openings 28a are plugs 31. Screwed within the openings 29a are plugs 32 and screwed within the openings 30a are plugs 33. The plugs 31 and 33 are closed, but attached to the plugs 32 are pipes 34 connected to the beer side of the bungs 35 extending into the beer barrels. The valve chambers 28, 29 and 30 on one side of the valve head communicate through the valve openings 36, 37 and 38 with a passage 39 disposed on one side of the valve head, whereas the valve chambers 28, 29 and 30 on the opposite side of the valve head are connected to a passage 39, disposed on the opposite side of said

valve head and being disposed symmetrically with respect to the first passage 39. The passages 39 are connected through passages 49 disposed on the opposite ends of the valve head with pipes 41 connected to the beer coils 19. The end walls 42 of the valve head are tapped, as at 43, receiving pipes 44 interconnected, as at 45, and leading through pipe 46 to a water supply under pressure.

10 As shown in Fig. 8 of the drawings, the pipes 44 communicate with the end chambers 30. Said end chambers are interconnected through a passage 48 disposed rearwardly of the chambers 28 and 29. The central pair of chambers 28 are interconnected through a pair of rearwardly and inwardly diverging passages 59, which meet and communicate with a downwardly extending drain pipe 51.

20 A pair of sliding piston valves 53, having stems 53a, slidably extending through packing glands 54 are provided with discs 55 at the lower ends thereof, adapted to close the openings 36 of the valve chambers 28. Coil compression springs 57 within chambers 28 mounted between the plugs 31 and the discs 55 serve to normally retain the valve in closed position for closing the openings 36 and cutting off communication between the chambers 28 and the passages 39.

30 A similar pair of valves 60 provided with stems 61 extending through packing glands 62 are provided with discs 63 at the lower ends thereof for closing the openings 37, and are retained normally in closed position by coil compression springs 69 within chambers 29 and interposed between the plugs 32 and discs 63. A third pair of valves 70 are provided with stems 71 extending through packing glands 72 and have discs 73 at the lower ends thereof for closing the openings 38. Said valves are normally retained in closed position by coil compression springs 74 within chambers 30 and interposed between the plugs 33 and the discs 73 for normally retaining the openings 38 closed to cut off communication between chambers 30 and the passages 39.

40 45 The valve casing 26 is provided with a pair of forwardly extending arms 76 and 77 formed with aligned bearing openings at the outer ends thereof, rotatably receiving a shaft 78. Fixed on said shaft 78 and disposed between the arms 76 and 77 are a pair of actuating arms 79 bifurcated at the outer end and supporting rollers 80. The arms 77 are aligned with respect to each other and are disposed in the planes of the valves 53. There is also fixed on the shaft 78 another pair 50 55 of arms 80 located on opposite sides of the central arm 79 and likewise bifurcated and supporting rollers 82. The arms 81 are aligned with respect to one another and are in the plane of the valve stems 61. Said arms 81 extend, however, in a direction opposite to the direction on the arm 79, thus being at 180° angular relation to said arms.

60 65 There is further fixed on the shaft 78 a third pair of arms 84 carrying rollers 85 at the ends thereof. The arms 84 are aligned with respect to one another and are in the plane of the valve stems 71. The arms 85 are located at an angle of 90° from both the arms 79 and 81. As shown in Figs. 2, 3, 4, 5 and 7, the arms 81 which actuate the beer valves, project upwardly. The arms 84 which control the water valves project rearwardly toward the wall 23, and the arms 79 which control the drain valves project downwardly, the shaft 78 being rotatable in a clockwise direction,

looking at Figs. 4, 5 and 7, or in a counter-clockwise direction, looking at Fig. 2.

5 Fixed to the casing 26 and disposed between the shaft 78 and the valve chambers is a vertical wall 90 extending between the arms 76 and 77. Fixed to the wall 90, as shown in Fig. 7, as by screws 91, are a pair of vertical brackets 92, each having an upwardly extending, bifurcated arm 93 supporting a pivot pin 94. The brackets 92 are aligned with the arms 79 and the valve stems 53a. 10 Pivoted on the pin 94 of each bracket and received within the bifurcated arms is an actuating lever 95 having a tapered downwardly extending projection 96 at the outer end thereof, located above one of the arms 79, and an arm 98 formed with a screw threaded opening 99 disposed above one of the valve stems 53a. An adjusting screw 100, provided with a lock nut, is screwed within each opening 99 and adapted to contact the upper end of one of the valve stems 53a. 20

The brackets 92 are each provided with edge portions 101 serving as a stop to limit clockwise rotation of the levers 95. It will be noted that normally the springs 57 within the chambers 28 pressing upwardly against the valves 53, retain the levers 95 in the position shown in Fig. 7. However, upon rotation of the shaft 78 the rollers 80 on the arms 79 will contact the projections 96 of the levers 95 to rotate said levers in a counter-clockwise direction and open the valves 30 53 to permit communication between the chambers 28 and the passages 39.

30 There is further attached to the wall 90, as shown in Fig. 4 of the drawings, brackets 102 similar to the brackets 92 and supporting levers 103 similar to the levers 95 and adapted to cooperate with the valves 60 controlling the beer chambers 29. The levers 103 may be actuated by the arms 81 for opening the valves 60 and permitting communication between the chambers 29 40 and the passages 39.

40 45 There is further fixed to the wall 90 as shown in Fig. 5 of the drawings a pair of brackets 106 similar to the brackets 92 and 102 and supporting a pair of levers 107 aligned with the valves 70 and the arms 84. The levers 107 are provided with adjusting screws 108 similar to the adjusting screws 100 and contacting the upper ends of the valve stems 71. Each of said levers 107 is further formed on one surface thereof with a 50 groove 109 and with an upstanding projection 110. Fixed to one side of each lever 107 is a strip 111 extending across the groove 109, forming a slot. Pivoted to the projection or lug 110, as at 112, and extending through said slot is a second lever 113 55 having an upwardly extending arm 115 and a downwardly extending cam 117 provided with a shoulder 118 adapted to contact the lever 107.

50 55 Coil tension springs 120 interconnect the upper ends of the arms 115 with the adjusting screws 108. The springs 120 normally tend to rotate the levers 113 in a counter-clockwise direction for retaining the shoulders 118 against the levers 107. It will be noted that when the arms 84 rotate in a clockwise direction and engage the underside of the cams 117, the levers 107 will be rotated in a counter-clockwise direction, as shown in Fig. 9 of the drawings, for opening the valves 70 and establishing communication between the water chambers 30 and the passages 39. However, upon rotating the arms 84 in a counter-clockwise direction, the rollers 85 will contact the lower ends of the levers 113 to rotate the same in a clockwise direction, as shown in Fig. 10 of the drawings, against the tension of 70 75

the springs 120, permitting the arms 84 to pass said levers without lifting the levers 107 or opening the valves 70.

The shaft 18 extends beyond the arm 77 of the casing 26, as at 18a, and fixed to said extending portion is a sheave 125. Said sheave is provided with a pair of stop lugs 126 and 127 adapted to contact stop members on the arm 77 to limit the angular rotary movement of said sheave in opposite directions. The sheave 125 may be formed with a peripheral groove 128. Received within the groove 128 of the sheave and extending around said groove, is a flexible element 130, the lower end of which is connected through a tension spring 131 to a fixed bracket 132.

The flexible element 130 is attached to a second flexible element 132, described in greater detail hereinafter, through a lost motion device 133. The device 133 may comprise a strap 134 connected to the lower end of the element 132 and provided with a portion 137 at the lower end thereof having an opening receiving the element 131 therethrough. The upper end of the element 131 is attached to a member 135 provided with a downwardly extending tubular portion 136 receiving the element 131. The lower end of the tube 136 is normally spaced above the lower portion 137 of the strap 134 and is retained in spaced position by a coil compression spring 138 received on the tube and interposed between the member 135 and the portion 137 of the strap 134. Should an upward pull be exerted on the flexible elements 132, said element will move a predetermined distance until the portion 137 of the strap 133 contacts the lower end of the tube 136 before movement is imparted to the flexible elements 131. A lost motion is thus provided between the elements 132 and 131.

The control device 16 which controls the valve head 25 comprises a casting 140 having a flat plate portion 141 fixed to the side of the bar counter 13, and a valve chamber portion 143, to the bottom end of which there is screwed a plug 144. Screwed to the plug 144 is a pipe 145 connected through pipe 146 to the air inlet ends of the bungs 35. The valve chamber 143 is furthermore formed with a tapped opening in the side wall thereof, to which there is attached a pipe 147 connected to the tank of the air pump 22. It will thus be noted that communication is always established between the pipes 145 and 147 through the chamber 143. At the upper end thereof the chamber is formed with a valve seat 149, provided with a valve opening 150 communicating with a chamber 151. The wall of the chamber 151 is formed with a screw threaded opening, to which there is screwed a pipe 152 connected to the pipe 18 and hence through the pipes to the beer coils 19.

Extending through a packing gland 154 on the casting 140 is a valve 155 comprising a valve stem 156 provided with a ball top and having a valve disc 157 at the lower end thereof, adapted to be pressed against the seat 149 by a coil compression spring 159 located within the chamber 143 for closing the opening 150 to cut off communication between said valve chamber and the pipe 152. The casting 140 further comprises a segmental vertical plate 160 parallel to the plate 141 and formed with a notch 161 in the periphery thereof, and with a second notch 162 close to the notch 161. Said plate 160 is further formed with a third notch 163 disposed substantially 90° from the notch 162 and with a fourth notch 164 disposed substantially 90° from the notch 163 and

180° from the notch 162. The notch 161 will be designated the beer notch, the notch 162 the return notch, the notch 163 the water notch, and the notch 164, the drain notch, for the purpose hereinafter appearing.

The plates 141 and 160 are formed with aligned bearing openings rotatably supporting a shaft 166. Fixed on one end of the shaft 166 is a pointer 167 disposed adjacent the outer surface of the plate 160 and adapted to point toward the notches in the periphery of said plate. There is further fixed to said shaft a handle 169 formed with a groove 170 in the outer face thereof. Received within the groove 170 is a lever 171 pivoted to the handle, as at 172, and having an upwardly extending arm 173 and a downwardly extending arm 174. A coil compression spring 175 received within the groove 170 and interposed between the bottom wall of the groove and said arm, normally tends to rotate the lever 171 in a counter-clockwise direction, looking at Fig. 12 of the drawings.

The arm 174 is adapted to be received in one of the notches 161, 162, 163 or 164, depending upon the angular position of the handle. When the arm 174 is received in one of the notches in the plate 160, the arm 173 projects somewhat beyond the handle. To release the arm 174 from the notch within which it is received, it is merely necessary to grasp the handle and press the arm 173 of the lever against the spring 175 to cause a clockwise rotation of the lever 171. Thereafter the handle 169 may be rotated about the axis of the shaft 166 to align the arm 174 with another notch. The handle 169 may be formed with a bore 180 to receive a key tumbler 181 of any standard construction, either key or combination operated, and provided with a projection 182 adapted to engage the arm 173 for locking the lever 171 with the arm 174 in one of the notches, for the purpose hereinafter appearing.

There is further mounted on the shaft 166 a sheave 190 formed with a peripheral groove 191 receiving the flexible element 132. One end of the flexible element 132 is fixed to the sheave 190, as at 193. The casting 141 may be formed with a guide tube 195 receiving the flexible element 132 therethrough and further receiving a cable protector 196 disposed about the flexible element.

There is further fixed on the shaft 166 a cam 170 having a raised portion 177 and a second raised portion 178 spaced from the raised portion 177.

With the handle 169 in the position shown in Fig. 11, the valve 156 is closed. However, upon turning the handle in a counter-clockwise direction, looking at Fig. 11, the raised portion 177 will press down on the upper ball end of the valve stem 156 to open the valve 155 when the arm 174 registers with the notch 162. Upon further turning the handle 169, the raised portion 177 passes the valve stem and the valve 155 is permitted to close. When the arm 174 reaches the water notch 163, the valve 155 is still closed. However, upon further rotating the handle 169 to the position where the arm 174 reaches the drain notch 164, the raised portion 178 of the cam 170 will press down again on the valve stem 156 and again open the valve 175.

The operation of my improved system will now be explained. Normally the parts are in the position shown in Figs. 1, 2 and 3. The arm 174 is received within the beer notch 161 and the arms 81 retain the valves 60 in open position, establishing communication between the cham- 75

bers 29 and the passages 39. Beer from the barrels 11 thus flows through the bungs and through the pipes 34 to the chambers 29, and through the passages 39 to the pipes 41, and hence to the beer coils 19. Air or gas pressure is supplied to the barrels 11 through the pipe 147 which is connected to the pump 22 through the chamber 143 and pipe 145 to the pipes 146, which are connected to the bungs 35. In this position of the parts beer may be dispensed by merely opening the faucets 17.

To prevent the beer from becoming stale overnight, the beer may be returned to the barrels by grasping the handle 169, pressing the lever 171 to release the arm 174 from the notch 161 and rotating the handle to bring the lever portion 174 within the notch 162. Upon rotating said handle, the valve 155 will open due to pressure of the raised portion 177 of the cam 170 against the upper end of the valve stem.

Upon opening the valve 155, communication is established between the valve chamber 143 and the pipe 152. Air pressure from the pipe 147 and also air or carbon dioxide pressure from the beer barrel 11 passing upwardly through the pipe 145, will be at an equal pressure due to inter-communication through chamber 143. Beer under the same pressure as the pressure in chamber 143 and pipes 145, 147 and 152 fills the pipes 20, coils 19, pipes 41, valve 60 and pipes 34. Thus with a balanced pressure in the system the beer will be allowed to flow downwardly through the coils 19 and through the valve chambers 29 and pipes 34, back into the beer barrels under the force of gravity. It will be noted that upon rotating the handle 169 from the notch 161 to the notch 162, the sheave 190 will rotate through a small angle without, however, causing any rotation of the sheave 125, by reason of the lost motion connection 133.

With the coils 19 empty, should it be desired to flush the coils for cleaning purposes, it is merely necessary to grasp the handle 149 and rotate the same to the position where the arm 174 will enter the notch 163. During this movement the valve 155 will close and the sheave 125 will be rotated to substantially 90°, thus causing the arms 81 to move off the levers 103 and permit closing of the beer valves 60. During this movement the shaft 78 is rotated to the position shown in Fig. 9 where the arms 84 will lift the levers 107 to open the water valves 71. In this position of the parts, beer cannot flow into the passages 39, since the beer valves 60 have closed. Water under pressure, however, from the pipe 46, passes to the pipes 44 and into the water chambers 30 and through said chambers to the passages 39 and through passages 49 to the pipes 41 and upwardly into the coils 19. Upon opening the faucets 17, water will flow through said faucets to thoroughly cleanse the coils 19.

When the coils have been sufficiently cleansed, the faucets 17 may be closed and the handle 169 thereafter moved to bring the arm 174 to the drain notch 164. This movement of the handle will cause rotation of the sheave 190 and consequently, rotation of the sheave 125 to rotate the shaft 78 to move the arms 84 off the levers 107 to permit closing of the water valves 71. The arms 79, however, are moved to an upward position for lifting the levers 95 and opening the drain valves 53. The valve 155 will also be opened by reason of engagement of the raised portion 178 of the cam 170 with the upper end of the valve stem 155.

75 Air pressure from the pump and tank passing

through the pipe 147 will then pass through the chamber 143 through pipe 152 for forcing the water downwardly through the beer coils, through the pipes 41, passages 39, drain chambers 28, and outwardly through the drain pipe 51. 5

After the water has been thoroughly drained from the beer coils, the handle 169 may be rotated back in the opposite or clockwise direction, looking at Fig. 2, to the original position thereof, for closing the drain valves and opening the beer 10 valves. During this movement, the water valves are not open, because the levers 113 are merely tripped, as explained above, without actuation of levers 107. Beer will then again flow from the barrels to the beer coils. The spring 131 pulling 15 downwardly on the cable or flexible element 130, facilitates movement of the handle 139 back to its original position.

It will be noted that the levers 107 are each provided with a handle extension 200 adapted to 20 be engaged by a finger of the operator. With this construction, after the beer barrels have been emptied, the water valves may be opened while the handle 169 is in the position shown in Fig. 2 with the beer valves also open. The water may 25 thus flow through the pipes 46 and 44 through the passages 39 and downwardly through the open beer valves, into the beer barrels for flushing and cleaning the barrels.

To prevent dispensing of beer, the lock 181 30 may be locked with the portion 174 in either the water notch 163 or the drain notch 164. In such positions the beer valves 60 are closed and it is not possible to dispense beer.

It will thus be seen that there is provided a 35 device in which the several objects of this invention are achieved, and which is well adapted to meet the conditions of practical use.

As various possible embodiments might be made of the above invention, and as various 40 changes might be made in the embodiment set forth, it is to be understood that all matter herein set forth or shown in the accompanying drawings is to be interpreted as illustrative and not in a limiting sense. 45

Having thus described my invention, I claim as new and desire to secure by Letters Patent:—

1. In a beer dispensing system, a beer coil connected to a faucet, a beer barrel having a bung inserted therein, a valve head formed with a passage communicating with said beer coil and a valve chamber communicating through a pipe with said bung, a valve controlling communication between said chamber and passage, a second chamber in said valve head communicating with a water supply under pressure, a second valve for controlling communication between said last chamber and said passage, a third valve chamber in said valve head communicating with a drain pipe, a third valve for controlling communication between said third chamber and said passage, and means for controlling said valves. 55

2. In a beer dispensing system, a beer coil connected to a faucet, a beer barrel having a bung inserted therein, a valve head formed with a passage 65 communicating with said beer coil and a valve chamber communicating through a pipe with said bung, a valve controlling communication between said chamber and passage, a second chamber in said valve head communicating with a water supply under pressure, a second valve for controlling communication between 70 said last chamber and said passage, a third valve chamber in said valve head communicating with a drain pipe, a third valve for controlling communication between said third chamber and said passage, and means for controlling said valves. 75

5 munication between said third chamber and said passage, a second valve head having a chamber connected by a pipe to an air supply under pressure, a passage in said second valve head connected by a pipe to said beer coil and a valve for controlling communication between said last chamber and said last passage.

3. In beer dispensing system, a beer coil connected to a faucet, a beer barrel having a bung inserted therein, a valve head formed with a passage communicating with said beer coil and a valve chamber communicating through a pipe with said bung, a valve controlling communication between said chamber and passage, a second chamber in said valve head communicating with a water supply under pressure, a second valve for controlling communication between said last chamber and said passage, a third valve chamber in said valve head communicating with a drain pipe, a third valve for controlling communication between said third chamber and said passage, a second valve head having a chamber connected by a pipe to an air supply under pressure, a passage in said second valve head connected by a pipe to said beer coil and a valve for controlling communication between said last chamber and said last passage, a rotary sheave mounted on said second valve head, means for opening the valves of the first valve head, including a rotary shaft and a sheave fixed thereto and flexible means interconnecting said sheaves for simultaneous rotation.

4. In a beer dispensing system, a beer coil connected to a faucet, a beer barrel having a bung inserted therein, a valve head formed with a passage communicating with said beer coil and a valve chamber communicating through a pipe with said bung, a valve controlling communication between said chamber and passage, a second chamber in said valve head communicating with a water supply under pressure, a second valve for controlling communication between said last chamber and said passage, a third valve chamber in said valve head communicating with a drain pipe, a third valve for controlling communication between said third chamber and said passage, a second valve head having a chamber connected by a pipe to the air side of said bung and by a second pipe to an air supply under pressure, a passage in said second valve head connected by a pipe to said beer coil and a valve for controlling communication between said last chamber and said last passage, a rotary sheave mounted on said second valve head, means for opening the valves of the first valve head, including a rotary shaft and a sheave fixed thereto, flexible means interconnecting said sheaves for simultaneous rotation, and means associated with said second valve head for actuating the valve in said second valve head.

5. In a beer dispensing system, a beer coil connected to a faucet, a beer barrel having a bung inserted therein, a valve head formed with a passage communicating with said beer coil and a valve chamber communicating through a pipe with said bung, a valve controlling communication between said chamber and passage, a second chamber in said valve head communicating with a water supply under pressure, a second valve for controlling communication between said last chamber and said passage, a third valve chamber in said valve head communicating with a drain pipe, a third valve for controlling communication between said third chamber and said passage, a second valve head having a chamber

connected by a pipe to the air side of said bung and by a second pipe to an air supply under pressure, a passage in said second valve head connected by a pipe to said beer coil and a valve for controlling communication between said last chamber and said last passage, a rotary sheave mounted on said second valve head, means for opening the valves of the first valve head, including a rotary shaft and a sheave fixed thereto, flexible means interconnecting said sheaves for simultaneous rotation, means associated with said second sheave for actuating the valve in said second valve head, and means for rotating said first sheave including a handle fixed for rotation with said sheave and means for retaining said handle in a plurality of predetermined angular positions.

6. In a beer dispensing device, a beer coil, a beer barrel, a valve head comprising a chamber connected to the beer side of a bung inserted into said barrel, said valve head being formed with a passage communicating through a pipe with said beer coil and with an opening interconnecting said chamber and passage, a spring pressed valve normally closing said opening, a second chamber within said valve head communicating with a water supply under pressure, said head having an opening connecting said second chamber with said passage, a spring pressed valve for closing said second opening, said head being formed with a third chamber communicating with a drain pipe and having a third opening connecting said third chamber with said passage, a spring pressed valve normally closing said third opening, means for opening said valves including a rotary shaft, and means associated therewith for selectively depressing said valves at different angular positions of said shaft.

7. In combination, a valve head having a passage and a plurality of chambers communicating with said passage through openings, spring pressed valves for closing said openings and means for opening said valves comprising a shaft having arms disposed at an angle to one another and levers pivoted to said valve head and adapted to be actuated by said arms at different angular positions of said shaft for selectively depressing said valves.

8. In a beverage dispensing device, a container for the beverage, a cooling coil, a valve head comprising a chamber connected by a pipe to said container and being formed with a passage communicating through a pipe with said coil and with an opening interconnecting said chamber and passage, a spring pressed valve slidably mounted on said valve head and normally closing said opening, a lever pivoted to said valve head and having one end overlying the upper end of said valve, a member rotatably mounted on said valve head adapted to engage the other arm of said lever for rotating the same to open said valve, a second valve head having a chamber connected by a pipe to said receptacle and by another pipe to a gas supply under pressure, said second valve head having a passage connected by a pipe to the coil and being formed with an opening between said last passage and chamber, a spring pressed valve slidably mounted on said second valve head and adapted to close said last mentioned opening, a member rotatably mounted on said second valve head and adapted to open said second valve, and means for simultaneously rotating said rotatably mounted members.

9. In a beverage dispensing device, a container for the beverage, a cooling coil, a valve head comprising a chamber connected by a pipe to said container and being formed with a passage communicating through a pipe with said coil and with an opening interconnecting said chamber and passage, a spring pressed valve slidably mounted on said valve head and normally closing said opening, a lever pivoted to said valve head and having one end overlying the upper end of said valve, a member rotatably mounted on said valve head adapted to engage the other arm of said lever for rotating the same to open said valve, a second valve head having a chamber connected by a pipe to said receptacle and by another pipe to a gas supply under pressure, said second valve head having a passage connected by a pipe to the coil and being formed with an opening between said last passage and chamber, a spring pressed valve slidably mounted on said second valve head and adapted to close said last mentioned opening, a member rotatably mounted on said second valve head and adapted to open said second valve, means for simultaneously rotating said rotatably mounted members, said second valve head being formed with a fixed portion having a plurality of notches, a handle fixed for rotation with said second rotatably mounted member, and a member movably mounted on said handle and adapted to selectively engage said notches.

10. In a beverage dispensing device, a container for the beverage, a cooling coil, a valve head comprising a chamber connected by a pipe to said container and being formed with a passage communicating through a pipe with said coil and with an opening interconnecting said chamber and passage, a spring pressed valve slidably mounted on said valve head and normally closing said opening, a lever pivoted to said valve head and having one end overlying the upper end of said valve, a member rotatably mounted on said valve head adapted to engage the other arm of said lever for rotating the same to open said valve, a second valve head having a chamber connected by a pipe to said receptacle and by another pipe to a gas supply under pressure, said second valve head having a passage connected by a pipe to the coil and being formed with an opening between said last passage and chamber, a spring pressed valve slidably mounted on said second valve head and adapted to close said last mentioned opening, a member rotatably mounted on said second valve head and adapted to open said second valve, means for simultaneously rotating said rotatably mounted members, said second valve head being formed with a fixed portion having a plurality of notches, a handle fixed for rotation with said second rotatably mounted member, a member movably mounted on said handle and adapted to selectively engage said notches, and means for locking said movable member against movement in any one of the notch engaging positions thereof to prevent rotation of said handle.

11. In a beer dispensing system, a beer coil connected to a faucet, a beer barrel having a bung inserted therein, a valve head formed with a passage communicating with said beer coil and a valve chamber communicating through a pipe with said bung, a valve controlling communication between said chamber and passage, a second chamber in said valve head communicating with a water supply under pressure, a second valve for controlling communication between said

last chamber and said passage, a third valve chamber in said valve head communicating with a drain pipe, a third valve for controlling communication between said third chamber and said passage, a second valve head having a chamber connected by a pipe to the air side of said bung and by a second pipe to an air supply under pressure, a passage in said second valve head connected by a pipe to said beer coil and a valve for controlling communication between said last chamber and said last passage, a rotary sheave mounted on said second valve head, means for opening the valves of the first valve head, including a rotary shaft and a sheave fixed thereto, flexible means interconnecting said sheaves for simultaneous rotation, means associated with said second sheave for actuating the valve in said second valve head, means for rotating said first sheave including a handle fixed for rotation with said sheave, means for retaining said handle in a plurality of predetermined angular positions, and means for locking said first shaft against rotation.

12. In a beer dispensing system, a beer coil connected to a faucet, a beer barrel having a bung inserted therein, a valve head formed with a passage communicating with said beer coil and a valve chamber communicating through a pipe with said bung, a valve controlling communication between said chamber and passage, a second chamber in said valve head communicating with a water supply under pressure, a second valve for controlling communication between said last chamber and said passage, a third valve chamber in said valve head communicating with a drain pipe, a third valve for controlling communication between said third chamber and said passage, a second valve head having a chamber connected by a pipe to the air side of said bung and by a second pipe to an air supply under pressure, a passage in said second valve head connected by a pipe to said beer coil and a valve for controlling communication between said last chamber and said last passage, a rotary sheave mounted on said second valve head, means for opening the valves of the first valve head, including a rotary shaft and a sheave fixed thereto, flexible means interconnecting said sheaves for simultaneous rotation, means associated with said second sheave for actuating the valve in said second valve head, means for rotating said first sheave including a handle fixed for rotation with said sheave, means for retaining said handle in a plurality of predetermined angular positions, said last means comprising a member pivoted to said handle and a notched member fixed with respect to said second valve head, said pivoted member being adapted to selectively engage said notches, and spring means for rotating said pivoted member.

13. In a beer dispensing system, a beer coil connected to a faucet, a beer barrel having a bung inserted therein, a valve head formed with a passage communicating with said beer coil and a valve chamber communicating through a pipe with said bung, a valve controlling communication between said chamber and passage, a second chamber in said valve head communicating with a water supply under pressure, a second valve for controlling communication between said last chamber and said passage, a third valve chamber in said valve head communicating with a drain pipe, a third valve for controlling communication between said third chamber and said passage, a second valve head having a chamber

connected by a pipe to the air side of said bung and by a second pipe to an air supply under pressure, a passage in said second valve head connected by a pipe to said beer coil and a valve for controlling communication between said last chamber and said last passage, a rotary sheave mounted on said second valve head, means for opening the valves of the first valve head, including a rotary shaft and a sheave fixed thereto, flexible means interconnecting said sheaves for simultaneous rotation, means associated with said second sheave for actuating the valve in said second valve head, means for rotating said first sheave including a handle fixed for rotation with said sheave, means for retaining said handle in a plurality of predetermined angular positions, said last means comprising a member pivoted to said handle and a notched member fixed with respect to said second valve head, said pivoted member being adapted to selectively engage said notches, spring means for rotating said pivoted member, and means for locking said pivoted member against movement.

14. In combination, a valve head having a chamber and a passage, and being formed with an opening interconnecting said chamber and passage, a valve mounted on said valve head and having a valve stem extending above said valve head and a disc adapted to close said opening, a spring within said chamber for retaining said disc in closing position, a lever pivoted to said valve head and having an arm overlying the upper end of said valve stem, and a second arm extending away from said valve stem, a second lever pivoted to the second arm of said first lever, a tension spring interconnecting an arm of the second lever to said first arm of said first lever for retaining the second arm of the second lever in engagement with the second arm of said first lever.

15. In combination, a valve head having a chamber and a passage, and being formed with an opening interconnecting said chamber and passage, a valve mounted on said valve head and having a valve stem extending above said valve head and a disc adapted to close said opening,

a spring within said chamber for retaining said disc in closing position, a lever pivoted to said valve head and having an arm overlying the upper end of said valve stem, and a second arm extending away from said valve stem, a second lever pivoted to the second arm of said first lever, a tension spring interconnecting an arm of the second lever to said first arm of said first lever for retaining the second arm of the second lever in engagement with the second arm of said first lever, and a rotary actuating member adapted to engage, when rotated in one direction, the second arm of the second lever to cause rotation of the first lever, and adapted to engage, when rotated in the opposite direction, the second arm of the second lever, to cause rotation thereof against the tension of said spring without causing rotation of said first lever.

16. In a beer dispensing system, a beer coil connected to a faucet, a beer barrel having a bung inserted therein, a valve head formed with a passage communicating with said beer coil and a valve chamber communicating through a pipe with said bung, a valve controlling communication between said chamber and passage, a second chamber in said valve head communicating with a water supply under pressure, a second valve for controlling communication between said last chamber and said passage, a third valve chamber in said valve head communicating with a drain pipe, a third valve for controlling communication between said third chamber and said passage, a second valve head having a chamber connected by a pipe to the air side of said bung and by a second pipe to an air supply under pressure, a passage in said second valve head connected by a pipe to said beer coil and a valve for controlling communication between said last chamber and said last passage, a rotary sheave mounted on said second valve head, means for opening the valves of the first valve head, including a rotary shaft and a sheave fixed thereto, flexible means interconnecting said sheaves for simultaneous rotation, and a lost motion device interposed in said flexible means.

ABRAHAM COHEN.
